UNITED STATES PATENT OFFICE

JOHN BATH, OF WORCESTER, MASSACHUSETTS

GRINDING MACHINE

Application filed April 4, 1927. Serial No. 180,741.

This invention relates to a grinding machine adapted for general purposes but particularly designed for the grinding of screw threads in taps and for grinding other threaded work.

It is the general object of my invention to provide improvements in the construction and arrangement of parts in such a machine, by which improvements the wear of certain parts may be reduced, the removal and replacement of parts may be facilitated, and the general operation of the machine may be made more reliable and satisfactory.

A preferred form of the invention is shown in the drawings in which

Fig. 1 is a partial plan view of the head end of a thread grinding machine;

Figs. 1^a and 1^b are detail plan views of certain parts shown in Fig. 1;

Fig. 2 is an end elevation of the machine, looking in the direction of the arrow 2 in Fig. 1;

Fig. 3 is an enlarged sectional elevation, taken along the line 3—3 in Fig. 1;

Fig. 4 is a transverse sectional view, taken along the line 4—4 in Fig. 3; and

Fig. 5 is an enlarged detail plan view of certain parts to be described.

Referring to the drawings, I have shown portions of a thread grinding machine comprising a base 10 having a wheel table 11 slidably mounted on guide-ways 12 and 13 formed on the rear portion of the base 10. A cross slide 14 is mounted on the wheel table 11 and supports the grinding wheel W.

Mechanism for rotating the work is mounted in a head 15, supported on the front portion of the frame 10. A worm 16 (Fig. 1^a) is mounted on a worm shaft 17 and is rotated in any convenient manner, as by a belt 18^a (Fig. 2) running over a pulley 18. The worm 16 engages a worm wheel 19 (Fig. 1) which is connected by bevel gears 20 and 21 to a pair of sliding change gears 22 and 23. These gears mesh selectively with change gears 24 and 25 on a drive shaft 26.

The head center 27 and face plate 28 by which the work is supported and rotated are mounted on a separate driving member 30 which is aligned with the drive shaft 26 but

is provided with entirely separate bearings. Power is transmitted from the shaft 26 to the member 30 by spiral gears 31, 32, 33 and 34 (Fig. 1^b), the gear 31 being on the drive shaft 26, the gears 32 and 33 being on an intermediate shaft 35, and the gear 34 being on the driving member 30.

I will now describe the driving connections between the drive shaft 26 and the wheel table 11, said connections forming an important part of my present invention. For this connecting mechanism I provide a bracket 40 (Fig. 1), bolted to the end of the base 10 and projecting longitudinally a substantial distance beyond the end of the base. In this bracket an outer bearing is provided for the drive shaft 26, which extends through the bracket and has a driving gear 41 secured to its outer end.

A series of change gears 42, 43, 44 and 45 are mounted on a supporting plate 47 which is secured to the bracket 40 by bolts 48, extending through arcuate slots concentric with a gear 49 which is aligned with a lead screw 50 (Fig. 1) by which the wheel table 11 is reciprocated. The plate 47 is centered on the axis of the gear 49 and lead screw 50 by a flange 52 (Fig. 3), extending into a circular opening or recess 54 in the bracket 40. The change gear plate 47 may thus be swung about the axis of the gear 49 to cause the uppermost change gear 42 to suitably engage the driving gear 41 and may be secured in such adjusted position.

The gear 49 is secured to the outer end of a short shaft 55, rotatable in a bearing hub 56 which is secured by bolts 57 to the inner face of the bracket 40 and which is provided with a projection 58 by which the hub is centered in the opening 54 previously described. The short shaft 55 is provided with a flanged inner end 60, which engages the inner end of the hub 56. A collar 61 is keyed to the shaft 55 and is longitudinally adjustable by a nut 62 threaded on said shaft. A binding screw 63 is also provided for retaining the adjustment of the nut 62. By suitably adjusting the sliding collar 61 with respect to the projection 58, any end play of the short shaft 55 may be eliminated.

The lead screw 50 for the wheel table 11 is provided with an extension 65 (Fig. 3), fitting a recess 66 in the flanged portion 60 of the short shaft 55. A collar or flange 67 is keyed to the extension 65 of the lead screw and is adapted to be secured firmly against the face of the flange 60 by a plurality of bolts or screws 68. A key block 70 (Figs. 1 and 3) is secured by a screw 71 in a slot in the edge of 10 the flange 67 and fits snugly into a slot 72 in the edge of the flange 60; thus preventing relative angular movement of the parts 60 and 67. By removing the bolt 68, however, the parts may be easily separated.

15 The nut for the lead screw 50 comprises two threaded portions 73 and 74, mounted in the bearing portion 75 of a nut bracket 76. Both nut portions 73 and 74 are keyed in the bearing portion 75 of the bracket 76, as indicated at 77 in Fig. 4. The nut portion 73 is forced into the bracket portion 75 and is intended to remain fixed therein. The nut portion 74, however, is provided with a threaded outer extension on which an adjusting nut 78 is mounted. By slightly turning the nut 78, the nut portion 74 may be drawn outward in the bracket portion 75, and by such slight longitudinal adjustment, any wear between the nut and the lead screw may be taken up.

20 The bracket 76 is secured by bolts 80 (Fig. 4) to a vertical bearing face 81, formed on the side of a recess 82 in the wheel table 11. A removable cap plate 83 ordinarily covers the recess 82, but may be removed to give access 25 to the bolts 80. One end of the recess 82 is cut away, as indicated in Fig. 1, and is provided with a filler piece 85 held in position by a bolt 86. A guard plate 87 (Fig. 4) is mounted on the base 10 and extends between 30 the wheel table 11 and the bearing bracket 76 in every position of the wheel table, thus effectively protecting the lead screw from dirt and abrasive.

Having described the details of construction of my improved grinding machine, the use and advantages thereof will be readily understood. In the first place, the provision of the longitudinally projecting bracket 40 removes the change gears and the lead screw 45 drive from the vicinity of the grinding wheel W, so that they are much less liable to injury from flying abrasives.

Furthermore, this offset construction permits me to use the separate shaft 55 and to 50 form a satisfactory driving connection between said shaft 55 and the lead screw 50. I am also able to accomplish this without limiting the travel of the wheel table, as would be the case if this construction were embodied in 55 a machine not having my outwardly projecting bracket.

Furthermore, I have provided a construction by which the lead screw may be quickly and easily removed for repairs or replacement, whenever this becomes necessary. In

accomplishing this result, I remove the bolts 68 connecting the collar 67 to the flange 60 (Fig. 3), and remove the bolt 86 which secures the filler piece 85. I then remove the plate 83, and the bolts 80 which secure the bearing bracket 76 to the wheel slide. I previously move the wheel table 11 toward its right hand limit of travel, as viewed in Fig. 3.

Having loosened the several connections as above described, I rotate the lead screw in its nut sufficiently to draw it out of the end of the shaft 55 and I am able to lift out the lead screw and its bearing bracket as a unit from the machine for making such adjustments or replacements as may be desired, all without removing the wheel table from the grinding machine. This is a very marked improvement over any previous machine of which I have knowledge, in which previous machines 85 it is commonly necessary to substantially dismantle the grinding machine in order to remove the lead screw therefrom.

Telescoping guards 90 and 91 (Fig. 5) on the bracket 40 and wheel table 11 afford additional protection for the lead screw drive.

Having thus described my invention and the advantages thereof, I do not wish to be limited to the details herein disclosed otherwise than as set forth in the claims, but what I claim is:—

1. In a grinding machine, a base, a wheel table slidable thereon, a lead screw for said wheel table, a nut for said lead screw, a bearing bracket for said nut, means to detachably secure said bracket on said wheel table, and means for adjusting said nut relative to said bracket and to said lead screw thereby to take up wear.

2. In a grinding machine, a base, a wheel table slidable thereon, a lead screw for said wheel table, a nut for said lead screw, a bearing bracket for said nut, and means to detachably secure said bracket on said wheel table, said securing means being mounted in a recess in said table, and said nut and lead screw being readily removable from said machine while said wheel slide remains mounted thereon.

3. In a grinding machine, a base, a wheel table slidable thereon, a lead screw for said wheel table, a nut for said lead screw, a bearing bracket for said nut, and means to detachably secure said bracket on said wheel table, said bearing bracket having an upstanding flange extending axially of said lead screw, and said table having an upright longitudinally extended bearing surface for engagement by said flange, and having clamping devices to secure said parts together.

4. In a grinding machine, a base, a driving shaft, a wheel table slidable on said base, a lead screw therefor mounted in offset relation to said driving shaft, and connections between said driving shaft and said lead

screw, said connections including a short shaft mounted in separate bearings aligned with said lead screw, and detachable connections between said short shaft and said lead screw.

5. The combination in a grinding machine as set forth in claim 4, in which said short shaft is provided with a flanged and recessed end, and said lead screw is provided with an extension centered in said recess, and with a collar adapted to be clamped against the flanged end of said short shaft.

10 6. The combination in a grinding machine as set forth in claim 4, in which said short shaft is provided with a flanged and recessed end, and said lead screw is provided with an extension centered in said recess, and with a collar adapted to be clamped against the flanged end of said short shaft, and
15 20 in which means is provided to prevent relative angular movement between said collar and flange.

7. In a grinding machine, a base, a driving shaft, a wheel table slidable on said base, a lead screw therefor mounted in offset relation to said driving shaft, and connections between said driving shaft and said lead screw, said connections including a short shaft mounted in separate bearings aligned with
25 30 35 said lead screw, and detachable connections between said short shaft and said lead screw, said short shaft and said driving shaft connection being mounted on a separate frame member projecting outwardly from the end of said base.

8. In a grinding machine, a base, a wheel table slidable thereon, a lead screw for said wheel slide, an outwardly projecting bracket fixed to the end of said base and having an opening aligned with said lead screw, a driving shaft mounted in offset relation to said lead screw, a driving gear thereon, and driving connections between said driving gear and said lead screw, including a short shaft mounted in separate bearings and aligned with said lead screw, said driving connections being mounted on and supported by said bracket.

9. In a grinding machine, a base, a wheel table slidable thereon, a lead screw for said wheel slide, an outwardly projecting bracket fixed to the end of said base and having an opening aligned with said lead screw, a driving shaft, a driving gear thereon, driving
50 55 60 connections between said driving gear and said lead screw including a train of change gears, a supporting plate for said change gears centered in said bracket opening and angularly adjustable about the axis thereof, said plate being mounted on said bracket, and means to secure said plate in angularly adjusted position with said change gears in operative relation to said driving gear.

10. In a grinding machine, a base, a wheel table slidable thereon, a lead screw for said

wheel table, a split nut having a plurality of screw engaging portions for said lead screw, a bearing bracket for said nut, means to detachably secure said bracket on said wheel table, and means to adjust one of said nut portions relative to said bracket and to said lead screw, thereby to take up wear, remaining portions of said nut being relatively fixed.

70 75 In testimony whereof I have hereunto affixed my signature.

JOHN BATH.
